UNITED STATES PATENT OFFICE.

JOHN F. WHITE, OF CHICAGO, ILLINOIS, ASSIGNOR TO WHITE PRODUCTS COMPANY, OF CHICAGO, ILLINOIS, A CORPORATION OF ILLINOIS.

THEFT-PREVENTING DEVICE.

Application filed October 29, 1920. Serial No. 420,549.

To all whom it may concern:

Be it known that I, JOHN F. WHITE, a citizen of the United States, residing at Chicago, in the county of Cook and State 5 of Illinois, have invented certain new and useful Improvements in Theft-Preventing Devices, of which the following is a specification.

This invention relates generally to theft 10 preventing devices, and more particularly to a device for controlling the operation of a screw nut or similar element utilized as a securing, attaching or retaining member for holding parts in assembled relationship. 15 In another aspect the invention relates to a form of closure or stopper adapted to be mounted upon the mouth of a conduit, a vessel or other container in a manner effective to retain the device against unauthorized removal therefrom.

One object of the invention is the provision of a theft preventing device in the nature of a nut controlling device, whereby a retaining member such as a nut, screw 25 cap, or the like, may be adjusted and seated upon a suitable pipe, post, or the like in such fashion as to retain an object thereon, and which device may then be purposely disabled, so far as operation of the nut or 30 retaining member is concerned, so that the latter cannot be operated for detachment, excepting in intended fashion through means or information supposedly under control of an authorized person only.

Another general object is the provision of such a device which may be adapted to a great variety of uses and applications without alteration of its essential features, which may be manufactured economically 40 and which will operate effectively under trying conditions of use without impairment of its function or utility.

Another object is the provision of such a device especially adapted to be incorporated 45 with a fitting or accessory instrument intended for attachment to certain mountings, which are more or less standard, without requiring any adaption or special fitting of the mounting.

A more specific object is the provision of such a device adapted particularly for use as a combined closure cap and instrument 50 retainer suitable for effective use upon the radiator tube of an automobile.

Another specific object of the invention is

the provision of such a device wherein the operation of the retaining member is dependent upon proper operation of a combination lock or similar element contained within the structure of the device itself. 60

Another specific and quite important object is the provision of such a device which, by virtue of its construction, is particularly adapted for embodiment in a pleasing and symmetrical form, whereby it is especially 65 appropriate for use on automobile radiator tubes as a means for operating a closure and retaining an instrument or ornament.

A still further and important object of the invention is the provision of a construction for a device of the sort described whereby proper positioning of movable portions for the purpose of unlocking or detaching may be made without requiring visual attention to the device, whereby such 75 operation may be accomplished in the dark.

Various other objects and advantages, both general and specific, of the invention will be pointed out hereinafter or will be obvious upon an understanding of the illustrative embodiment herein disclosed or will 80 be indicated in the appended claims.

In the accompanying drawing forming a part of this specification I have shown a preferred form and modifications thereof for 85 the purpose of illustrating the invention, but it is to be understood that I do not regard this particular disclosure as exhaustive of the range or variety of modifications or adaptations in which the essential features of the invention may be utilized. The disclosure, therefore, is not to be regarded 90 as limiting the invention short of its true scope.

In the said drawing— 95

Fig. 1 represents a sectional elevation of an embodiment of the invention illustrating its application to a radiator tube closure;

Fig. 2 is across section substantially on line 2—2 of Fig. 1; 100

Fig. 3 is a detail, being an elevation of the form of retaining member shown in Figs. 1 and 2;

Fig. 4 is another detail, being a diametrical section of the housing member shown 105 in Fig. 1;

Fig. 5 is a view similar to Fig. 3 but showing a modified arrangement of lock connection;

Fig. 6 is a view similar to Fig. 4 but show- 110

ing a modified form of lock member suitable for cooperation with the form of retaining member illustrated in Fig. 5; and

Fig. 7 is a sectional view on line 7—7, of Fig. 1, illustrating the lock dials.

Fig. 8 is a vertical section of a device embodying my improved audible or tactile indicator for the positioning of the locking portions.

Fig. 9 is a cross sectional view of the same;

Fig. 10 is a diametrical section of the operating member of such a device showing its association with the retaining member viewing the same in the direction of the arrow 10 in Fig. 9;

Fig. 11 is a similar diametrical section but looking in the direction indicated by the arrow 11 of Fig. 9, and

Fig. 12 is a sectional elevation of a modified embodiment showing an adaptation of the invention to an internally threaded tube.

Referring to the drawings in detail by means of the reference characters applied, let it be understood that the numeral 1 designates the upper extremity of a radiator tube of an automobile, having its upper portion screw-threaded or otherwise formed for the attachment and adjustment thereon of a retaining member 2. This is here illustrated in the form of a collar substantially cylindrical exteriorly and formed internally for adjustable engagement with the mounting 1, on which it may be adjusted by rotary movement.

When designed for the purpose of securing a tight closure, this retaining member is preferably provided with an inwardly directed flange 4 adapted to overlie the rim of the mounting 1, and forming a seat for an upper packing ring 6 and for a lower packing ring 5 adapted to bear upon the upper surface of the mounting 1. Encompassing the retaining member 2 is a housing member 7, preferably formed with reference to the retaining member so that they are held in concentric relationship for relative rotary movement, and the two may be retained in assembled relationship by means of a ring 8 secured at the open side of the housing below the retaining member.

Where the device is designed as a closure, the housing has a cover portion overlying the flange 4 and making contact with the packing ring 6 carried thereby, so that a close joint is provided. This cover portion may constitute a mounting place for an instrument or ornament, designated by the character C, and the housing has a depending skirt portion encircling the retaining member, which skirt portion carries laterally projecting arm portions 9, one of which may be formed solid and the other of which is bored longitudinally. Rotatably mounted on the outer extremity of the arm members 9 are balls or other handle members 10,

preferably of similar design and contour. Seated within the longitudinally bored arm member is a rotatable shaft 11, held against withdrawal by suitable means, here illustrated by pin 12 seated in the arm 9 and adapted to travel in the space afforded by a reduced portion 14 of the shaft 11. Said reduced portion is of suitable extent to permit a certain amount of sliding movement of the shaft 11. At its outer end the shaft 11 is fixed to the handle member 10 so that it may be rotated and moved longitudinally by manipulation thereof. At the inner extremity of the shaft 11 is mounted an engaging member 15 adapted for engagement with the retaining member 2 when in an intended position determined by the rotary adjustment of housing 7 and the shaft 11. In the form illustrated in Figs. 1, 2, 3 and 4 the engaging member 15 is in the form of a cylindrical lug or post adapted for fitting engagement in an aperture or seat 16 formed in the retaining member 2. The engaging member 15, being eccentric with reference to the shaft 11, is engageable in the seat 16 only when the shaft is positioned accurately at the proper adjustment.

In Figs. 5 and 6 is illustrated another form in which the engaging member and seat may be embodied, and wherein the engaging member, here designated as 15', is of irregular form, and adapted to register accurately in the seat 16', so that they may be engaged only at the proper rotary adjustment of the shaft.

The handle members 10 are provided with suitable dials 10^a bearing indicating devices, and the adjacent portions of the arms 9 are provided with position indexes 9^a, the said dial and positioning index associated with the shaft 11 cooperating to provide the desired guide for positioning the engaging member 15, and the dial and positioning index on the other arm being effective to produce a symmetrical appearance and a means of confusing an uninitiated or unauthorized operator.

From the foregoing description the operation of the device is obvious, it being understood that, in order to effect adjustment of the retaining member 2 upon the mounting thereof for the purpose of positioning or removing it, the housing and shaft 11 must be placed in the proper rotary positions, and the latter then pushed inwardly to engage the member 15 in the seat 16. This locks the retaining member for rotation with the operating member,—which comprises the housing 7, arms 9 and handles 10,—so that the device may be attached to or removed from the mounting by rotary movement. By such operation, which may be effected conveniently by manipulation of the arms, the retaining member may be screwed down until its flange makes sealing

- engagement with the upper extremity of the mounting. The shaft then being retracted by outward movement of its connected handle member 10 and rotated from locking position, the operating member is rendered free for rotary movement relative to the retaining member, and may be positioned at the desired angle. Frictional engagement of the packing ring 6 against the housing portion is effective to retain the operating member at the desired angular position with sufficient security to prevent its displacement by the vibrations incident to normal operation of an automobile.
- When the device is in this condition removal of the retaining member 2 is inhibited, as it will not be rotated by the frictional engagement of the operating member, and it is completely housed so that it cannot be manipulated in an unauthorized fashion. To effect its detachment, therefore, the operating member must be placed at the proper angular position relative to it, the lock shaft 11 placed at the proper rotary adjustment, and the engaging member 15 shifted into seat 16 by the proper longitudinal movement of the shaft.
- The cooperation of the packing ring 6 with the other parts of the device is effective to prevent leakage of steam between the retaining member and the operating member, thus keeping the steam in the circulating system of the engine and protecting the locking mechanism from the effects thereof. With the device in position on the nipple the retaining means of the display device is concealed in a position where it is inaccessible so that theft thereof is prevented. Moreover the closure permits the positioning of the bulb or temperature responsive element of an indicating device such as a motor meter in proper position in the radiator nipple so that it will perform its normal functions.
- For the purpose of facilitating operation of the device in the dark, an audible or tactile indicating means may be incorporated in the structure, as illustrated in Figs. 8 to 12 inclusive. In this arrangement the arm 9 opposite that housing the lock shaft is longitudinally bored to form a channel for the reception of a longitudinally slideable tappet 17 having a reduced portion 17^a forming a detecting member operating in a reduced bore through the wall of the housing portion 7. The length of this detecting portion is such that it projects beyond the internal face of the housing 7 when the shoulder formed by the end of the tappet is in abutment with the end of the bore in which it slides. The tappet is yieldably held in this position by a spring 18 which is retained under compression by a collar 19 carried on the end of the handle member 10, which is rotatably held in the bore by a pin
- 20 riding in a reduced annular channel portion of the handle shank.
- The outer cylindrical face of the retaining member 2 is provided with a series of depressions 2^a arranged to align and register with the projecting detecting member 17^a of the tappet 17 and permit the terminal shoulder of the latter to contact with the end wall of the bore. These depressions 2^a are provided in a code series, which, as illustrated for example in Fig. 9 reading from the top the series is 4, 2, 4, 5, 4, 2, 4, and constitute location guides whereby the rotary position of the operating member relative to the retaining member may be determined by one having knowledge of the code arrangement. As the operating member is rotated, the detecting member 17^a will traverse the peripheral face of the retaining member and fall into the successive depressions 2^a successively, producing at each such occurrence an audible click, or an impulse perceptible to the touch, caused by the impact of the shoulder of the tappet against the end wall of the bore. The position of the lock seat 16 or 16' relative to the guide depressions being known to the operator, he will be enabled to position the operating member at proper rotary position to permit engagement of the locking member in the seat upon proper rotary adjustment of the shaft 11, which, once the operating member is in proper position, may be effected entirely by the sense of touch. Obviously the lock seat may be positioned opposite any one of the guide depressions 2^a or opposite a space intermediate any of them, and in this way, as well as by the great number of permutations and combinations permitted by arrangements of the guide depressions, a practically limitless number of variations is obtainable. The end of the detecting member 17^a is suitably formed to permit its being cammed out of the guide depressions upon rotation of the operating member, and the lock seat 16' may be likewise suitably formed to accommodate movement of the member 17^a by having portions of the wall in the path of the latter suitably channelled, as designated at 16^a. Obviously, guide depressions should be formed adjacent the lock seat so as to make the latter one of the series, so far as operation of the tappet is concerned.
- In Fig. 12 I have shown a fashion in which this form of mechanism may be adapted to use on an internally threaded tube or conduit. In this embodiment the retaining member 2 is peripherally threaded for engagement within the threaded mounting portion 1, and is supplemented with an exterior portion 2' which carries the lower packing ring 5 and the upper packing ring 6, and has a skirt portion depending to en-

compass the upper part of the mounting 1, and upon which the mounting portion 7 is rotatably guided. In this encompassing portion 2' are provided the lock seat 16' and guide depressions 2^a and with it cooperates the retaining ring 8 which holds the operating member in assembly thereon.

Certain of the features herein disclosed but not claimed are claimed in my co-pending applications Ser. No. 419,402, filed October 25, 1920, and Serial No. 411,255, filed September 18, 1920.

I claim:

15. An attachment of the class described comprising an operating member having a housing portion and laterally extending handles for manipulation thereof, a retaining member rotatably mounted within the housing portion and equipped for attachment to a suitable mounting by rotary movement, and locking means operable by one of said handles for engaging the retaining member for rotation with the operating member.
20. 2. The combination with a receptacle of an operating member having a housing portion arranged to form a closure therefor, a retaining member disposed within the housing for adjustable engagement with the receptacle, means cooperating with the retaining member and the housing to form a seal therebetween while permitting their relative rotation, said operating member including means for manipulating the housing and means for locking the retaining member for rotation therewith.
25. 3. An instrument retaining closure for automobile radiators comprising the combination of a housing member and a retaining member mounted co-axially for relative rotation, said retaining member having a top aperture to receive an instrument and being adapted for attachment to a radiator nipple by rotary movement, the housing member having portions effective to close said aperture and to prevent access to the retaining member, and locking means carried by the housing and movable thereon toward the common axis for engagement with the retaining member to permit rotation thereof by the operating member.
30. 4. In a closure device of the class described, the combination of a retaining member arranged for attachment to a suitable receptacle by rotary movement, an operating member mounted thereon for co-axial rotary movement and adapted to form a closure for such receptacle, the retaining member being provided with a laterally opening seat of predetermined form, and a radially shiftable engaging member movably mounted on the operating member and adapted to be positioned by rotary movement for fitting registration with said seat.
35. 5. In a device of the class described, the

combination of a retaining member adapted for screw thread connection to a mounting, an operating member housing the same and conjoined thereto for relative rotary movement, locking means for connecting said members to permit rotation of the retaining member by the operating member, and means for producing an audible indication of their relative position.

6. In a device of the class described, the combination of a rotary retaining member adapted to engage a mounting by rotary movement, a rotary operating member, said members carrying cooperating locking means for inter-engaging the two, and signal means for indicating relative location of the locking means on the respective members.

7. In a device of the class described, the combination of a rotatable retaining member adapted to engage a mounting by rotary movement, a rotatable operating member including laterally extending handles whereby it may be actuated, locking means operable in one of said handles for engaging the operating and retaining members, and signal means operable in another of said handles to indicate relative position of said members.

8. A theft preventing closure device comprising the combination of a retaining member adapted to screw onto a suitable mounting, a cap member rotatably connected with the retaining member and shaped to house the same, locking means supported on the cap member for connecting it to the retaining member, and signal means carried by the retaining member and cap member for operative association and effective upon relative movement of the two to produce audible signals as a guide for the positioning of the locking means.

9. In an automobile radiator closure, the combination with a retaining member, of an operating member adapted for co-axial rotation thereon, said retaining member being adapted for attachment to a radiator nipple and said operating member constituting a closure for the nipple and the end of the retaining member, said operating member including symmetrically disposed manipulating handles extending radially therefrom, and locking means operable in one of said handles to lock the operating member to the retaining member.

10. An automobile radiator closure comprising a tubular member having an annular wall portion, a cap adapted for rotation on said tubular member, said cap having a cover portion arranged to form a closure for the end of said tubular member and a skirt portion arranged to encompass the annular wall, operating handles extending laterally from said skirt portion and adapted for manipulation to rotate the cap, a bolt

- movably mounted in one of said handles and adapted to engage the annular wall portion to lock the cap to the tubular member, and means at the extremity of said handle 5 whereby said bolt may be actuated.
11. In an automobile radiator closure, the combination with a nipple of a cap adapted to form a closure therefor, said cap having 10 symmetrically arranged laterally extending arms whereby it may be rotated on the nipple, and engaging means for securing the cap to the nipple, said engaging means including a lock member housed in one of said arms and an operating member engageable 15 at the outer extremity of said arm for operating said lock member.
12. As an article of manufacture, a closure for automobile radiators comprising the combination with a tubular cylindrical supporting member, of a cap rotatably associated therewith as a closure, said cap being provided with laterally extending handles whereby it may be rotated to effect its attachment and detachment, said cap affording 20 a mounting for an ornament between said handles, and a locking bolt movably housed in a handle and adapted to be projected into locking engagement with the cylindrical member to secure the cap thereto.
13. A radiator closure comprising a cap portion forming a cover for the radiator nipple, an operating arm extending laterally from the cap whereby it may be manipulated, and locking means housed within the 25 arm and operable from the outer end thereof, said locking means having an engaging portion housed in the cap and movable into and out of engagement with the nipple for connecting and disconnecting the cap and 30 nipple.
14. A radiator closure comprising a cap body forming a cover for the radiator nipple, a collar having engagement with the nipple and rotatable connection with the cap 35 body, an operating arm extending from the cap body whereby the cap may be adjusted, and locking means housed within the arm and operable from the outer end thereof for connecting the collar and the cap body to 40 retain them against relative rotation, said locking means including a shiftable shaft in the handle and an engaging element movable thereby into and out of engagement with the collar.
15. A radiator closure comprising a cap body forming a cover for the radiator nipple, a collar having rotatable engagement with the nipple and loosely enveloped by the cap body, an operating arm extending from 45 the cap body, and locking means housed within the arm and operable from the outer end thereof for connecting the collar and the cap body whereby to enable the rotation of the collar on the nipple.
16. A theft-preventing attachment for automobile radiators, comprising the combination of a substantially cylindrical tubular member provided with a laterally opening recess, a cap rotatably associated with said tubular member and including a cover portion arranged to close the end thereof, and a depending skirt portion adapted to encompass the tubular member and cover said recess, a sealing gasket cooperating with the tubular member and cover portion, and a movable locking member housed below the cover portion and arranged for cooperation with the wall of said recess to secure the cap against rotation relative to the tubular member.
17. In a theft preventing device, the combination of a tubular retaining member engageable with a suitable mounting by rotary movement, an operating member housing the retaining member and rotatable relative thereto, and engaging means housed by the operating member at the outer side of the retaining member and adapted for engagement with the retaining member to permit rotation of the latter by the former, said operating member closing the end of the tubular retaining member to prevent access of vapor therefrom to the engaging means.
18. In a theft preventing device, the combination of a retaining member adapted for connection with a tube by rotary movement, an operating member housing the retaining member and co-axially mounted for rotation relative thereto, said retaining member and operating member cooperating to close an end of such tube when mounted thereon, engaging means housed in the operating member and operable to secure the retaining and operating members together, and means cooperating with said retaining member and operating member to prevent access of steam from the tube to the engaging means.
19. An automobile radiator closure comprising the combination of a retaining member adapted for attachment to a radiator nipple, an operating member housing the retaining member and covering an end thereof to form a closure for the nipple, means rotatably connecting the retaining and operating members, a sealing device cooperating with the retaining and operating members to prevent leakage of steam between them, and an engaging member concealed by the retaining and operating members for securing them for rotation together.
- In testimony whereof I have hereunto signed my name in the presence of two subscribing witnesses.

JOHN F. WHITE.
